CLAIM

The ornamental design for a display screen, or portion thereof, with graphical user interface, as shown and described.

DESCRIPTION

FIG. 1 is a front view of a display screen, or portion thereof, with graphical user interface showing our new design in a first embodiment;

FIG. 2 is a front view thereof in a second embodiment;

FIG. 3 is a front view thereof in a third embodiment; and,

FIG. 4 is a front view thereof in a fourth embodiment.

The dashed line showing of the display screen forms no part of the claimed design.

1 Claim, 4 Drawing Sheets
